PORTABLE IRONING MACHINE

Thomas James Little, Jr., Syracuse, N. Y., assignor
to Easy Washing Machine Corporation, Syra-
cuse, N. Y., a corporation of Delaware

Application March 25, 1940, Serial No. 325,822

10 Claims. (Cl. 38—60)

My invention is concerned with improvements in ironing machines especially of the portable type.

An object of my invention is to provide a compact, efficient, portable ironing machine that is inexpensive to construct and light in weight so that it may be easily carried about.

Another object of my invention is to provide in a portable ironing machine wherein the motor and driving mechanism are contained within a hollow roll, a simple means for mounting the roll whereby the roll may be removed quickly and easily to uncover the driving mechanism and motor.

Another object of my invention is to provide supporting means for the roll and for the shoe which cooperate to provide for self-alignment between the roll and the shoe.

Still another object of my invention is to provide supporting means for the roll and the shoe which cooperate to provide yielding pressure engagement between the roll and the shoe when these parts are moved into operative relationship, and wherein the supporting members themselves provide resiliency sufficient to accomplish this object without the use of springs.

Another object of my invention is to provide a unique means for supporting the shoe which comprises a single member at least a portion of which may be submitted to torsional strain, thus providing a yielding pressure engagement between the shoe and the roll when these parts are brought into cooperative relationship.

A further object of my invention is to provide supporting means for the roll and shoe so constructed and arranged as to give a maximum clearance for the free passage of the materials being ironed at the supported end of the roll.

Still another object of my invention is to provide a simple, manually operated toggle mechanism for subjecting the shoe supporting member to a torsional strain.

Another object of my invention is to provide electrical means for obtaining variations in the speed of the roll in an ironing machine wherein the motor and drive mechanism are contained within the roll.

Another object of my invention is to provide a centrifugal switch for interrupting the current supplied to the driving motor so as to obtain a reduced speed of the driving roll in order that the ironing time of an article may be increased.

Other objects and advantages of my invention will appear from the following specification taken

in connection with the accompanying drawings, in which:

Figure 1 is a perspective view of an ironing machine embodying the improvements of my invention.

Figure 2 is a rear elevation of the ironing machine shown in Figure 1.

Figure 3 is a schematic wiring diagram for said ironing machine.

10 Figure 4 is a partial vertical section, parts being broken away, taken in the vertical plane passing generally through the longitudinal center line of the machine.

Figure 5 is a view of the spring member of the centrifugal switch taken on the line 5—5 of Figure 4.

Figure 6 represents the roll driving gear train taken generally on the line 6—6 of Figure 4.

Figure 7 is a view of the overrunning clutch.

20 Figure 8 is a partial plan view of the base, parts being broken away, taken on the line 8—8 of Figure 4.

Figure 9 is a transverse vertical section taken on the line 9—9 of Figure 4.

25 Figure 10 is a view taken on the line 10—10 of Figure 9.

Figure 11 is a detail of the end of the operating lever.

Figure 12 is a detailed section, parts being broken away, taken on the line 12—12 of Figure 10.

Figure 13 is a detailed section taken transversely of the shoe.

Figure 14 is an exploded section similar to Figure 13.

35 Figure 15 is a partial elevation parts being broken away, showing the shoe operating handle in two positions.

Referring now more particularly to Figures 1 and 2, the machine comprises the base 20, the roll support 21, the roll 22, the shoe support 23 and the shoe 24. The motor 25 and driving mechanism 26 are contained within the roll, as shown in Figure 4.

The base member 20 is preferably stamped from 45 sheet metal and comprises a substantially shallow inverted trough 30 which is open at the bottom. (See Figures 4 and 9.) In the preferred form, this trough is deeper at the rear than in the front in order to accommodate mechanism later to be described. The bottom is closed by means of a cover plate 31 suitably secured by means of the brackets 32 and screw studs 33. A channel-shaped member 34 is secured within the base transversely thereof, preferably by spot welding. The member 34 serves the double pur-

50

pose of rendering rigidity to the top surface of the trough 30 while providing means for supporting mechanism presently to be described. In order to prevent scratching a surface upon which the machine may be placed, I have provided the rubber piece 35 which extends around the base and projects below the bottom thereof.

The roll supporting member 21 is preferably formed from a piece of metal tubing shaped generally in the form of a U, as shown in Figure 4. The lower arm 36 of the U is flattened somewhat, as shown in Figure 8. An aperture 37 of corresponding shape is provided in the end of the base member 20. A second aperture 38 of similar shape is provided in the cross member 34. In forming the aperture 38, a portion of the member 34 is bent over to form the bracket 39 into which is threaded a set screw 40. The lower arm 36 is inserted into the apertures 37 and 38 and rigidly secured therein by means of the set screw 40. The upper arm 41 of the supporting member 21 is provided at its free end with a female thread 42 for a purpose presently to be described.

On the arm 41 and substantially directly over the end of the base 20 is secured a spider 45 which, in the preferred form, has three arms 46 spaced substantially 120° apart. Adjacent the outer ends of the arms 46 are mounted the anti-friction rollers 47 by means of the studs 48. The guard member 49 is secured to the spider arms 46 by means of the brackets 50 and screws 51. The guard member 49 is provided with a plurality of apertures 52 to permit the circulation of air therethrough. The motor 25 and driving mechanism 26 are secured to the supporting member 41 by means of the flanged member 55 which is provided with a central boss 56 having a male thread 57 which is screwed into the female thread 42 to secure the member 55 to the supporting arm 41.

A supporting frame 58 is secured to the member 55 by means of a plurality of studs 59. The motor 25 is in turn secured to the supporting frame 58 by means of the screws 60. A bearing sleeve 61 is mounted on the arm 41 adjacent the end thereof. Driving spider 62 is mounted with a running fit over the bearing sleeve 61. A retaining member 63 is rigidly secured to the support 41 by means of the set screw 64 and serves to limit the endwise motion of the spider 62.

The spider 62 carries an internal gear 67 which, through the gear train 68 shown in Figure 6, is connected to the motor 25. An overrunning clutch 69 is provided in the gear 68 so that when the motor is stopped, the roll may be freely revolved by hand. The spider 62 is provided with a plurality of driving arms 70 (Figure 9). The outer end of each of said arms 70 is provided with a groove 71 for a purpose presently to be described.

The roll 22 comprises a metal cylinder 72 having suitable padding 73 and pad cover 74. A plurality of lugs 75 which, in the preferred form are stamped inwardly of the inner surface of the cylinder 72, are formed complementary to the grooves 71 in the ends of the arms 70 of the drive spider 62. The proportions of each of these lugs are such as to form a tight sliding fit with a corresponding groove 71 so that when the roll is in place, the roll will turn with the spider 62 without wobbling. The position of the anti-friction rollers 47 is so arranged as to snugly support the inner end of the roll 22 while permitting rotation thereof. The roll 22 is secured against

endwise motion by a single bracket 76 rigidly secured at one end by the screw 77 to the spider 62. The outer end of the roll 22 is provided with a plurality of inwardly extending brackets 78 one of which is provided with an aperture and a screw 79 to secure the roll to the bracket 76. A substantially conical guard 80 provided with the apertures 81 is secured to the brackets 78 by means of the screws 79 and 82 to close the opening at the free end of the roll while allowing circulation of air through the apertures 81.

The motor 25 is preferably of the shaded pole induction type and is provided with an armature shaft 85 which projects a substantial distance beyond its supporting bearings. The inner end of the shaft 85 is provided with gear teeth 86 adapted to mesh with the first gear in the train 68.

Adjacent the opposite end of the shaft 85 is mounted a centrifugal switch 87. An insulating sleeve 88 is mounted on shaft 85 and carries a pair of slip rings 89. A pair of brushes 90 are supported on insulating bushings 91 and contact the slip rings 89. The radial member 92 is mechanically and electrically fastened to one of said slip rings 89. The spring member 93 has one end rigidly fastened to the member 92. The member 93 extends inwardly and a substantial distance across the shaft 85 and at an angle thereto. Adjacent the free end of the spring member 93 is fastened a contact point 94. A second radial member 95 is electrically and mechanically fastened to the other slip ring 89 and has a contact point 96 fastened adjacent the outer end thereof positioned to cooperate with the contact 94 on the spring member 93. When the armature of the motor 25 rotates, centrifugal force tends to separate the contacts 94 and 96 because of the angularity of the member 93 with respect to the shaft 85.

At the extreme outer end of the shaft 85 is secured a fan 97 for the purpose of forcing a cooling current of air over the motor when the machine is operated.

In order to provide an efficient shoe and one in which the heating element may be operated at high ratings while insuring long life to the heating element, I prefer to construct the shoe in the following manner:

The sole plate 98, which extends substantially the length of the roll 22 is provided with retroverted edges 99 for a purpose presently to be described. An electric heating unit 100 is placed next to the sole plate. The heating unit comprises a resistance element here shown in two sections 101 extending longitudinally of the unit and secured between two sheets of mica 102 or other suitable electrical insulating material. A heat insulating pad 103 is placed over the heating unit 100. The back plate 104 is provided with two depressions 105 extending longitudinally thereof and positioned so as to press the pad 103 downward over the portions of the heating unit 100 containing the resistance elements 101 to form said unit into intimate contact with the sole plate 98 when the shoe is assembled. This structure reduces the resistance of the heat flow path from the electric resistance unit 101 to the sole plate 98. In assembling the shoe, the back plate 104 is slid lengthwise and secured in place by pressing the rods 106 and 107 inwardly under the edges 99, thus firmly clamping the back plate 104 in position.

A finger guard 108, preferably formed of a piece of metal tubing, is mounted in front of the for-

ward edge of the shoe on heat insulating collars 108 which are in turn supported on the inturned ends of the rod 107. The guard 108 is designed to keep the operator's fingers out of contact with the shoe.

The shoe support 23 comprises a substantially U-shaped member, having an upper arm 110 and a lower arm 111. The lower arm 111 is slightly offset to the front as shown in Figure 9, but extends substantially parallel to the arm 110. The lower arm 111 is rotatably supported in the base 20 by inserting it in suitable apertures provided in the end of the base 20 and in the cross member 34 as indicated at 112 and 113 of Figure 8. A groove in the arm 111 adjacent its end and the ring 114 serve to hold the arm in the assembled position. The shoe 24 is secured to the upper arm 110 of the support 23 in a manner presently to be described. It becomes apparent that turning the arm 111 in its supports 112 and 113 will swing the shoe 24 toward and away from the roll 22.

The mechanism for swinging the shoe comprises a toggle 115 (Figure 8) one end of which is secured by means of the pivot 116 to a lug 117 extending outwardly of the member 34. The other end of the toggle 115 is pivotally secured to the lever 118 which, in turn, is rigidly fastened to the member 111 by means of a set screw 119. In the preferred form, one link 120 of the toggle is a turnbuckle which may be extended or contracted, thereby increasing or decreasing the effective throw of the toggle. One end 121 of a link 122 is bent at right angles thereto and used as the pivot between the two toggle links. The portion 121 is here shown as secured in place by means of a cotter pin 123. The opposite end 124 of the link 122 is bent at right angles to the portion 121 and is secured by means of a cotter pin 125 in a short lever 126 which is rigidly fastened to a rock shaft 127.

The rear end of the shaft 127 is journaled to the back plate of the base 20, as shown at 128. The forward end of the shaft 127 is journaled at 129 in the forward wall of the base 20 and projects therethrough. Shaft 127 is held in place by means of the groove and snap ring 130, as indicated in Figure 8. The forward end of the shaft 127 is provided with a hexagonal socket 131 and a counterbore 132.

The detachable operating handle 135, preferably formed of hexagonal stock, is bent in the form of an L. The upper end of the operating handle is provided with a ball 136 or other suitable fixture adapted to fit the hand of the operator. The arm 137 of the rod 135 has a short cylindrical portion 138 formed adjacent the end thereof, the outer end of which is tapered, as at 139. (See Figure 11.) The portion 138 is split, as at 140. The split cylindrical portion 138 is so proportioned as to provide a frictional fit in the counterbore 132 in the member 127. Thus, the operating handle 135 may be readily inserted in the socket 131 while being maintained with some reasonable degree of security when in place.

When the handle 135 is moved to the left, as shown in Figure 1, rock shaft 127 will be rotated to the left, the lever 126 will throw the connecting link 122 to the left and straighten the toggle 115. As the toggle 115 is straightened it will rotate the lever arm 118 which, in turn, twists the arm 111 and will thus swing the shoe 24 into contact with the roll 22. The turnbuckle 120 is adjusted so that when the toggle is straight-

ened it will not only bring the shoe into contact with the roll but will give an additional twist to the lower arm 111, thus subjecting the arm to a torsional stress. As the arm 111 is made of an elastic metal, it will hold the shoe 24 with yielding pressure against the roll 22. As both the roll support 21 and the shoe support 23 are formed of substantially U-shaped members, both of these members will twist slightly when the roll and shoe are forced into contact.

Furthermore, as varying thicknesses of material are passed between the roll and the shoe, due to the resiliency of the supporting members 21 and 23, the roll and shoe will separate allowing the material to pass between them.

If the operator desires to have both hands free to guide the work into the machine, the handle 135 may be inserted in the socket 131 so that the handle 135 hangs downwardly as shown by the broken lines in Figure 15. With the handle 135 in the downward position and extending below the table on which the machine is being used, the handle may be operated by the knee.

The shoe 24 is secured to the arm 110 of the shoe support 23 in the following manner:

A bowl shaped depression 140 is formed in the back plate 104 substantially centrally thereof. The head 141 of a bolt 142 is inserted in this depression with the threaded shank extending outwardly from the plate 104. A bracket 143 having suitable apertures is passed over the threaded portion of bolt 142 and secured to the back plate 104 by means of the screws 144 and 145. Suitable backing pieces 146 and 147 are provided into which the screws 144 and 145 are threaded. Sufficient clearance is provided so that the bolt 142 may be turned by means of the slot 148. A threaded aperture is provided in the arm 110 adjacent the end thereof, into which the bolt 142 may be threaded. A second aperture is provided to accommodate the extension 150 of the screw 145. Thus, the screw extension 150 and the bolt 142 serve to maintain the shoe 24 in alignment with the arm 110 of the shoe support 23. If it becomes desirable to adjust the shoe 24 so that it is brought into greater or less pressure contact with the roll 22, this may be accomplished by inserting a screwdriver in the slot 148 of bolt 142 and turning the bolt so as to move the shoe relative to the arm 110. The lock nut 151 is provided to lock the bolt 142 in the adjusted position. It is contemplated that factory adjustment of the shoe pressure will be obtained by adjusting the turnbuckle 120 of the toggle mechanism 115. The additional adjustment feature of bolt 142 is provided so that pressure adjustment can be made quickly and easily in the field as compression of the roll pad 73 may require.

Affixed to the back plate 104 of the shoe 24 and substantially at the center thereof is a housing 153 which is provided with louvres 154 to permit circulation of air therethrough. Mounted within the housing is a thermostatic switch 156 which is provided with a handle 157 located on the outside of the housing 153. Within the housing 153 is also a light socket 158 for supporting an electric light bulb 159. The socket 158 is mounted on the bracket 143. The front face of the housing 153 is punched out to form the letters "Hot." The purpose of the louvres is to allow air to circulate through the housing to cool the light bulb 159 and thus increase its useful life.

The electrical wiring of the apparatus will now be described. Contained within the base 20 is a

self-winding cord reel 160 on which is wound a suitable length of two conductor cable 161. One end of the cable 161 projects through an aperture provided in the base member 20 and is connected to the attachment plug 162. The other ends of the cable 161 are connected to the slip rings 164 and 165 schematically indicated in Figure 3. A pair of brushes 166 contact the slip rings 164 and 165 to which all internal electrical connections are made.

Two wires 167 and 167' lead from the brushes 166 upwardly through the tubular shoe supporting member 23 into the housing 153. These leads are connected to either side of the light socket 158. Lead 167 is connected directly to the heating unit 100. The other lead 167' is connected through the thermostatic switch 156 to the other side of the heating unit 100. The thermostatic switch 156 is provided with four positions—an off position when the circuit is entirely broken, a high, a medium and a low heat position. When set in one of these heat positions, as soon as the shoe attains the desired temperature, the thermostatic switch opens. When the temperature drops below a prescribed limit, the thermostatic switch closes again and repeats the opening and closing, as required, to govern the temperature.

It is here to be noted that the light 159 will always be on whenever the attachment plug 162 is connected to a source of electrical energy, and this is so whether or not the thermostatic switch is in the off position and whether or not the motor is running.

Three motor control switches are provided. The manual switch 170 is connected to the lead 167, the other side of the switch 170 being connected to a switch 171. Switch 171 is mounted on the cross member 34 and has a push contact member 172 which is disposed in the path of the toggle joint 121. Thus, when the operating handle 135 is moved so as to straighten the toggle joint 121 and bring the shoe into contact with the roll, switch 171 is automatically closed. The other pole of switch 171 is connected directly to the motor 25. Switch 173, shown in Figure 3, is used for changing the speed of the motor 25. One side of the switch 173 is connected directly to the motor 25, the other side being connected to the lead 167'. Thus when switch 173 is in the closed position and switches 170 and 171 are closed, the motor 25 is connected directly to the line and the motor runs at normal speed.

The centrifugal switch 87 is used to obtain less than normal speed of rotation of the motor 25. One side of the switch 87 is connected directly to the motor 25, the other side of switch 87 is connected to bridge the switch 173 to the lead 167'. Thus, when switch 173 is opened, the current will pass through the centrifugal switch 87 to reach the motor 25. The tension of the spring arm 93 is set to permit the contacts 94 and 96 to separate when motor 25 attains half normal speed, and thus cut off the current supply. As the motor speed varies around the set speed, the switch opens and closes, thus maintaining the desired speed within narrow limits of variation.

A spark suppressor circuit comprising a resistance 175 and condenser 176 may be provided, connected across the contacts 94 and 96 of the centrifugal switch 87.

If it is desired to close the shoe against the roll without rotating the roll, switch 170 may be opened, in which case, the motor will not start

when the operating handle 135 is thrown to bring the shoe in contact with the roll. This is desirable for pressing operations.

To place the ironing machine in operation, the cable 161 is pulled out by means of the plug 162 until a sufficient length of cable is available for connecting the plug 162 to any convenient wiring outlet. Immediately upon plugging into a source of electric energy, the lamp 159 will light up in the indicator located on the ironer shoe. Thermostatic switch 156 is then set by means of the handle 157 to a temperature suitable for ironing any particular material. This temperature will vary from a low temperature for silk to a high temperature for linen. The thermostatic switch 156, when cold, closes the circuit through the heating element 100. When the temperature of the shoe has risen to the selected point, the thermostatic switch 156 will open thereby cutting off the source of current to resistance 100 and thereafter will periodically close and open, maintaining the temperature of the shoe within a reasonable range of selected temperature. For operation of the roll at normal speed, switch 170 is moved to the "on" position, and likewise switch 173. The operator places a piece of material to be ironed on the roll and then advances the roll slightly by hand to bring the edge of the material under the edge of the ironer shoe. The handle 136 is then swung to the right, which moves the shoe into contact with the ironer roll and at the same time closes switch 171, which sets the motor into operation, causing the roller to revolve and carrying the material to be ironed around with the roll and beneath the ironer shoe. If the operator desires to stop the roll with the material in the ironing position, it is only necessary to throw the switch 170 to the "off" position. This is called the pressing position of the switch 170. Operation of the handle 136 to open and close the roll will not start the motor when the switch 170 is in the "off" or pressing position. If the operator desires to operate the roll at half speed, the switch 173 is placed in the open position or, as indicated on the name plate, in the "off" position. This breaks the direct connection of the motor to the line 167' and the circuit is completed through the brushes 90 and the centrifugal switch 87. In this position, with the switch 170 closed, when the handle 136 is moved to the right to close the shoe against the roll, switch 171 is closed and the electric circuit is completed from the line 161 through the motor and centrifugal speed switch 96. If the speed of the motor exceeds a predetermined amount, the switch 96 opens, causing the motor to slow down. As the motor speed drops below the predetermined speed, the switch 96 closes, thus by the rapid opening and closing of the switch 96 the speed of the motor and hence the speed of the roll are controlled. This speed is set at the factory to be approximately one-half normal speed.

Although I have shown a specific embodiment of my invention, it is obvious that minor changes could be made in the form and relation of the parts thereof without departing from the spirit of my invention. I therefore wish to be limited only by the scope of the appended claims.

I claim:

1. In an ironing machine having a base, a shoe, a roll and means for obtaining relative movement between said shoe and roll to bring said members into and out of cooperative relation to each other, in combination, a substantially U-shaped support one arm of which is secured to said base, means

for rotatably mounting said roll on the other arm of said support, and a second substantially U-shaped support, one arm of which is rotatably mounted in said base, the other arm of which is secured adjacent the end thereof to substantially the center of said shoe, said supports being formed of metal tubing cooperating to yieldingly maintain said shoe and said roll in cooperative pressure engagement to allow for varying thicknesses of material passing therebetween when said roll and shoe are moved into cooperative engagement.

2. In an ironing machine having a base, a roll, a movable shoe adapted to cooperate with said roll and means for rotatably mounting said roll over said base in substantially rigid relation thereto, in combination, an unitary substantially U-shaped tubular support for said shoe, the lower arm of said support being rotatably mounted in said base, the upper arm of said support being secured adjacent the end thereof to substantially the center of said shoe, and means for rotating the lower arm of said support so as to swing said shoe into and out of pressure engagement with said roll.

3. In an ironing machine having a base, a roll, a movable shoe adapted to cooperate with said roll and means for rotatably mounting said roll over said base in substantially rigid relation thereto, in combination, a resilient unitary shoe support comprising a substantially U-shaped tubular member, the upper arm of which is secured adjacent its end to substantially the center of said shoe, the lower arm of which is rotatably supported in said base longitudinally thereof, a bearing member in said base adjacent the end thereof adapted to support said lower arm adjacent the bend of said U, a second bearing member in said base in spaced relation to said first bearing and adapted to support said lower arm adjacent the end thereof, and means operatively connected to said lower arm intermediate said bearings for rotating said lower arm to swing said shoe into and out of pressure engagement with said roll.

4. In an ironing machine having a base, a roll, a movable shoe adapted to cooperate with said roll and means for rotatably mounting said roll over said base in substantially rigid relation thereto, in combination, a resilient unitary shoe support comprising a substantially U-shaped tubular member, the upper arm of which is secured adjacent its end to substantially the center of said shoe, the lower arm of which is rotatably supported in said base longitudinally thereof, a bearing in said base adjacent the end thereof adapted to support said lower arm adjacent the bend of said U, a second bearing in said base in spaced relation to said first bearing and adapted to support said lower arm adjacent the end thereof, and means operatively connected to said lower arm adjacent the end thereof for rotating said lower arm to swing said shoe into cooperative relation with said roll and to subject said lower arm to torsional strain, thereby maintaining said shoe in yielding pressure engagement with said roll.

5. In an ironing machine having a base, a roll rotatably mounted over said base, and a movable shoe adapted to cooperate with said roll, in combination, means for swinging said shoe into and out of cooperative engagement with said roll including a substantially U-shaped support, the upper arm of which is disposed substantially parallel to the axis of said roll, means for secur-

ing said upper arm adjacent its end to substantially the center of said shoe, means for rotatably mounting the lower arm of said support in said base, and means for rotating said lower arm including a toggle mechanism operatively connected thereto remote from the connecting portion between the arms of said U-shaped support, whereby said lower arm may be subjected to torsional strain to maintain said shoe in yielding pressure engagement with said roll.

6. In an ironing machine having a base, a roll rotatably mounted over said base, and a movable shoe adapted to cooperate with said roll, in combination, means for swinging said shoe into and out of cooperative engagement with said roll including a substantially U-shaped support, the upper arm of which is disposed substantially parallel to the axis of said roll, means for securing said upper arm adjacent its end to substantially the center of said shoe, means for rotatably mounting the lower arm of said support in said base, a toggle mechanism operatively connected with said lower arm and adapted to rotate the same whereby said lower arm may be subjected to torsional strain to maintain said shoe in yielding pressure engagement with said roll, and adjusting means included in said toggle mechanism for varying the pressure between said shoe and said roll.

7. In a power driven ironing machine having a base, a hollow roll, a motor and driving mechanism contained within the roll, in combination, a supporting member rigidly secured to said base extending upwardly therefrom, thence horizontally and longitudinally of said base, means for rigidly securing said motor adjacent the free end of said support, a spider having a plurality of arms rigidly secured to said horizontal portion of said support adjacent the upwardly extending portion thereof, bearings secured adjacent the ends of said arms adapted rotatably to support one end of said roll, a rotatable spider having a plurality of driving arms mounted adjacent said motor and operatively connected thereto, an axially extending groove in the end of each driving arm, a plurality of lugs complementary to said grooves formed in the inner surface of said roll to allow a sliding fit therebetween, a longitudinal bracket rigidly fastened to said spider and extending toward the outer end of said roll, a bracket rigidly fastened to the inner surface of said roll adjacent the end thereof, and disconnectable means for fastening said brackets together to secure said roll in place.

8. In an ironing machine having a roll, an electric motor and driving mechanism contained within the roll for rotating the same, in combination with a source of electric power, an electric circuit connecting said source of power to said motor, a speed responsive switch in said circuit for making and breaking said circuit automatically, and a second switch bridging said speed responsive switch.

9. In an ironing machine having a roll, an electric motor and drive mechanism contained within the roll for rotating the same, in combination with a source of electric power, a speed responsive make and break switch operatively connected to said motor and arranged to open when the motor speed exceeds a predetermined value and to close when said motor speed is at or below the predetermined value, said switch being electrically connected between said source of electric power and said motor to control the speed of said motor, and a second manually op-

erated switch connected to bridge said speed responsive switch, whereby said roll is operated at normal speed when said manual switch is closed or at less than normal speed when said manual switch is opened.

10. In an ironing machine having a roll, an electric motor and drive mechanism for rotating said roll and wherein said motor and drive mechanism are mounted within said roll, in combination with a source of electric power for said motor, external means for controlling the operating speed of said roll including a two position manually operated switch, a speed responsive current interrupting switch operatively connected to said motor, one side of said latter switch being

5 electrically connected to one terminal of said motor, the other side of said latter switch being connected to one point of said manual switch and one side of said source of power, and the other point of said manual switch being connected directly to said motor terminal, whereby when said manual switch is in the closed position said motor is connected directly to said source of electric power and when said manual switch is in the open position said motor is connected through said speed responsive switch to said source, thereby permitting said roll to be operated at either of two predetermined speeds.
